[57] CLAIM

The ornamental design for a hand held remote control, as shown and described.

DESCRIPTION

FIG. 1 is a top, left perspective view of the hand held remote control, showing our new design;

FIG. 2 is a front perspective view thereof;

FIG. 3 is a left side elevational view thereof;

FIG. 4 is a right side elevational view thereof;

FIG. 5 is a rear plan view thereof;

FIG. 6 is a top plan view thereof, the broken line showing of the buttons is for illustrative purposes only, and forms no part of the claimed design; and,

FIG. 7 is a bottom plan view thereof.
